United States Patent [19]

Yang

[11] Patent Number: Des. 298,833

[45] Date of Patent: ** Dec. 6, 1988

[54] **MACHINE FOR CUTTING WORKPIECES UTILIZING ELECTRICAL DISCHARGE**

[76] Inventor: Shun T. Yang, No. 49, Lane 265, Tai Ping Road, Tai Ping Hsiang, Taichun Hsien, Taiwan

[**] Term: 14 Years

[21] Appl. No.: 846,562

[22] Filed: Mar. 28, 1986

[52] U.S. Cl. D15/127

[58] Field of Search ..... D15/127; 219/68, 69 R, 219/69 G, 69 W

[57] **CLAIM**

The ornamental design for a machine for cutting workpieces utilizing electrical discharge, substantially as shown and described.

DESCRIPTION

FIG. 1 is a perspective view of a machine for cutting workpieces utilizing electrical discharge showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 1

FIG. 2.

FIG. 3.

FIG. 4.

FIG. 5.

U.S. Patent

Dec. 6, 1988

Sheet 6 of 7

D298,833

FIG. 6.

FIG. 7.
